BUNDLE SEALING MACHINE

William L. Irvine, Brooklyn, N. Y., assignor to
 The American Sugar Refining Company, New
 York, N. Y., a corporation of New Jersey

Application February 4, 1947, Serial No. 726,418

18 Claims. (Cl. 93—6)

1

This invention relates to machines for closing and sealing the tops of bags of heavy paper stock, commonly referred to as bundles, which are used in the distribution of small sealed packages of such products as sugar, coffee, and similar commodities. More particularly, the invention is concerned with an improved folding and sealing mechanism which may be used, for example, in the bundle closing and sealing machine disclosed in my Patent 2,372,578, issued March 27, 1945. The novel mechanism is superior to that in the machine of the patent in that it makes folds with sharp well-defined fold lines, and thus insures tight sealing of the bundles without manual intervention.

In the machine of Patent 2,372,578, the bundles with their tops open are advanced in upright position by conveying means to a station, at which the bundles come to rest and part of the folding and sealing operations are performed on them. While a bundle is standing still at the station, a pair of arms swing in a horizontal plane to engage the rear end wall of the top of the bundle and force it inwardly, after which the arms move outwardly against the side walls and form them partially into flaps. An adhesive is then applied to the inner surface of the front end wall and a plate, swinging on a horizontal axis, engages the front end wall and folds it down upon the infolded rear end wall. In this operation, the plate completes the formation of the side walls in the flaps. The bundle is next moved away from the station and, during its movement, the flaps are coated with adhesive on their upper surfaces and then folded inwardly upon the infolded end walls.

The means disclosed in the patent for folding the rear end wall of the top of the bundle inwardly and the side walls outwardly are of somewhat complicated construction, in that the arms are given a non-circular movement by means of cams. Also, the combination of the arms and the plate does not always form the side walls into flaps with sharp folding lines, because of the heavy stock of which the bundle is made, and, unless the flaps are uniform and sharply folded, it is difficult, because of their small size, to cause them to adhere firmly to the infolded end walls.

The present invention is, accordingly, directed to the provision of an improved sealing and closing means for operation on the tops of bundles of heavy relatively stiff stock or having multi-ply walls, and the new means are of simple construction and produce uniform side wall flaps,

2

which can be tightly sealed in place. A machine equipped with the new means operates rapidly and the sealed bundles issuing from it require no manual operations to complete partial seals.

5 For a better understanding of the invention, reference may be made to the accompanying drawings, in which:

Fig. 1 is a vertical longitudinal sectional view, on the line 1—1 of Fig. 3, of a machine provided

10 with the new closing and sealing means;

Fig. 1A is an elevational view of parts shown in Fig. 1;

Fig. 2 is a top plan view with parts shown in section;

15 Fig. 3 is a sectional view on the line 3—3 of Fig. 1;

Figs. 4—8, inc., are diagrammatic views showing the operations of certain parts of the mechanism; and

20 Figs. 9 and 10 are perspective diagrammatic views showing the operations of certain other parts.

The machine illustrated in the drawings is generally of the same construction as that disclosed

25 in Patent 2,372,578, except for the new folding means. The machine is constructed for closing and sealing bundles containing twelve 5 lb. bags of sugar, and each such bundle is about 22½" long from its bottom to its top, when the upper

30 end is open, and its cross-sectional dimensions are about 7½" x 15". The bundles 11 are filled with the bags at a filling station and then delivered on a conveyor belt 12 to the closing and sealing machine. The bundles enter the machine 35 while standing erect and are advanced through it broadside on.

The machine includes a frame made up of side and cross frame members 13 and the bundles are moved through the machine, while supported on

40 a series of rolls 14. Pairs of vertical shafts 15 are mounted in suitable bearings at each end of

the frame, and each shaft carries upper and lower sprocket wheels 16. Chains 17 are trained

45 about each pair of sprocket wheels in each level at both sides of the machine. The upper and lower chains at each side of the machine are

50 connected by conveyor plates 18 and, as a bundle is advanced on belt 12, it enters a pocket formed between front and rear pairs of plates 18. The

55 shafts 15 are driven through bevel gearing from a shaft 19, which is, in turn, driven by a chain 20 from a main drive shaft 21. Shaft 21 is driven

through a chain 22 trained about a sprocket wheel 23, which is fast on a shaft driven through

a reduction box 24 by a motor 25.

As a bundle is advanced toward the intake end of the machine, it may be directed by an attendant between conveyor plates 18 on the chains 17 and the machine may then be started to cause the bundle to advance to the station, at which the bundle 11 is shown in Fig. 1. Preferably, however, the machine may include means shown in the patent, by which a bundle advancing on belt 12 causes the conveyor chains 17 to be moved. As the bundle approaches the station, the chains are stopped, so that the bundle may remain at rest, until certain folding operations have been performed, after which the chains are again started and the bundle discharged from the machine. The means by which the chains are started, stopped, and started again may be of any well-known type and are preferably those disclosed in my prior patent.

A horizontal rock shaft 26 is mounted in bearings in upward extensions 27 from the opposite side frame members and the shaft is provided with an arm 28 connected by a rod 29 to one arm of a bell crank 30 loosely mounted on a horizontal shaft 31, extending between the side frame members. The other arm of the bell crank 30 is connected by a rod 32 to a lever 33 having a follower entering a groove in a cam 34 on a shaft 35. Shaft 35 is driven by a chain 36 trained about a sprocket wheel on drive shaft 21 and rotation of cam 34 acts, through the parts described, to rock shaft 26.

A horizontal rock shaft 37 is mounted in bearings in the side frame members of the machine below shaft 26 and shaft 37 is provided with an arm 38 connected by a rod 39 to one arm of a bell crank 40 loose on shaft 31. The other arm of the bell crank is connected by a rod 41 to a lever 42, having a follower entering a groove in a cam 43 on shaft 35. A pair of hook-shaped holding plates 44 are mounted on shaft 37 and, in the operation of the machine, plates 44 move from the upper dotted line position in Fig. 1 to the lower full line position. When plates 44 are in the full line position, their forward edges 44a extend upwardly and rearwardly at an angle of about 60° to the horizontal.

A pair of arms 45 are mounted loosely on shafts 26 and 37 and extend downwardly below shaft 37. A rock shaft 46 is mounted in bearings in the lower ends of the arms and it is connected by a chain 47 to rock shaft 26. A folding plate 48 is mounted on shaft 46 and extends outwardly substantially in a plane through the axis of the shaft.

A pair of vertical rock shafts 49 are mounted on the side frame members and are provided at their lower ends with arms 50, each of which is connected by a universal link 51 to the end of a lever 52 pivoted on the frame work of the machine at 53. Lever 52 has a roller 54 entering a track in cam 55 on shaft 35. At its upper end, each rock shaft 49 carries a sprocket wheel 56 connected by a chain 57 to a sprocket wheel 58 on a vertical rock shaft 59 journalled in the frame members. Each rock shaft 59 carries a folding plate 60, the two plates lying in the same horizontal plane.

A glue vessel 61 is mounted in extensions from the frame above the folding station, and one end of the vessel is closed by a distributing roll 62 driven through gearing and a chain 63 from a shaft 64, which is, in turn, driven through a chain 65 from shaft 21. A pair of inclined guideways 66 are formed in upward extensions from the frame of the machine and rolls 67 at the

end of a cross-bar 68 run in the guideways. The cross-bar is connected by links 69 to levers 70 pivoted on the frame extensions and the levers are rocked by rods 71 actuated by cams (not shown) to move the cross-bar back and forth along the guideways. The cross-bar is formed with forwardly extending arms 72, in the ends of which is mounted a gluing-roll 73. When the cross-bar is in its uppermost position, roll 73 comes in contact with roller 62 and takes up glue therefrom.

When a bundle comes to rest at the station in the position shown in Fig. 1, shafts 59 are rocked to cause arms 60 to swing, so that their ends engage the rear end wall 74 of the top of the bundle (Fig. 4) and fold this wall inwardly against the top of the contents. At this stage in the operation, the plate 48 is in vertical position and in contact with the front end wall of the bundle and the holding plates 44 are elevated. When the rear end wall of the bundle has been folded inwardly, shaft 37 is rocked to swing holding plates 44 down to the position illustrated in Fig. 5. In this position, the lower ends of the edges 44a of plates 44 engage the inner surface of the front end wall of the bundle close to the top of the contents therein. The plate 48 then moves to an inclination of about 45° (Fig. 6) and stops. During that movement, the gluing roll 73 has been moved down to the lower end of its travel and has also been moved toward plate 48 by reason of the offset portions 66a in guideways 66. In this position, the glue roll lies between the holding plates 44 and, when the plate 48 comes to rest in inclined position, the inner surface of the front end wall of the bundle is in contact with the roll 73. The cross-bar 68 is then moved upwardly and, during that movement, roll 73 applies glue to the inner surface of the front wall of the bundle. When the roll 73 has passed beyond the end of the bundle, plate 48 is moved down further to fold that portion of the front end wall of the bundle between plates 44 into contact with the infolded rear end wall 74. In such movement of plate 48, the plate also folds the top wall of the bundle tightly about the inclined edges 44a of the holding plates 44, to form the side walls of the bundle into triangular flaps 75.

When the operations above described have been completed, the conveyor chains 17 are started in their operation and the bundle begins to move on through the machine. During the early part of this movement, the holding plates 44 and the folding plates 60 are swung back to inactive position, while the plate 48 remains down. Just beyond the folding station, are mounted a pair of stationary folding means or plows 76, which engage the flaps 75 and move them outwardly to horizontal position, as the bundle advances. When the bundle has passed from beneath plate 48, the latter is swung to its initial vertical position.

As the bundle passes beneath plows 76, its top is engaged by a plate 77, on which rests a weight 78, and the plate holds the infolded end walls of the top of the bundle in tight contact. The plate is held against movement with the bundle by loops 79 on a shaft 80 provided with a pair of presser rolls 81, which flatten the flaps 75 against presser rolls 82 on a shaft 83. Shaft 80 is driven through a chain 84 on shaft 64 and is geared to shaft 83. Shaft 64 is provided with a pair of glue rolls 85, which close the ends of glue vessels 86. The flattened flaps 75 issuing from

between rolls 81, 82 are glued on their upper surfaces by rolls 85 and as the flaps pass from beneath rolls 85, they are turned upwardly by stationary folding members 87.

A pair of reciprocating folding plates 88 are mounted beyond the glue rolls and each plate has a slot 89, through which extends a pin 90. Each plate also has a slot 91, through which extends one end of a shaft 92 carrying a cam 93, which acts on cam followers 94, 95 on the under surface of the plate. As the cam rotates, the plate is moved inwardly at an angle of about 45° to the path of travel of the bundle. The glued flaps moving beyond the folding members 87 are engaged by the plates 88 and folded downwardly on top of the infolded end walls. The plates 88 are free to move up and down and each plate is biased toward down position by springs 96, 97 encircling pin 90 and shaft 92, respectively.

As the bundle leaves the last roller 14, it is transferred to a conveyor belt 98, the upper stretch of which runs over rollers 99. An upper belt 100 has a lower stretch running beneath rollers 101, and belt 100 is held against the top of the sealed bundle to hold the infolded parts in position until the adhesive sets. Belt 98 and belts 100 are driven by any suitable means.

In the operation of the new machine, the front and rear end walls of each bundle are folded one upon the other and glued together and, at the same time, the side walls are formed into triangular flaps around the inclined edges of the holding plates. These operations result in the production of uniform flaps with sharp edges, and such flaps can be tightly sealed to the infolded end walls, even though the flaps are of relatively small size and the stock is stiff. The new folding mechanism, accordingly, operates to produce tightly sealed bundles and completion of the sealing of the flaps by hand operations is avoided.

I claim:

1. In a machine for closing and sealing the tops of bundles, the combination of means for advancing a bundle with an open top in upright position, a pair of folding members movable in a horizontal plane for forcing one end wall of the top inwardly, a pair of holding members movable into the top to engage the inner surface of the second end wall of the top, a plate engageable with the outer surface of the second end wall between the holding members, means for applying adhesive to the inner surface of the second end wall, means operable after the application of the adhesive to move the plate to force the second end wall inwardly upon the first end wall, while the holding members remain in position, and form the side walls of the top into flaps, means for applying adhesive to the inner faces of the flaps, and means for folding the flaps inwardly upon the infolded end walls.

2. In a machine for closing and sealing the tops of bundles, the combination of means for advancing a bundle with an open top in upright position, a pair of folding members movable on vertical axes for forcing one end wall of the top inwardly, a pair of holding members movable into the top to engage the inner surface of the second end wall of the top, a plate engageable with the outer surface of the second end wall between the holding members, means for applying adhesive to the inner surface of the second end wall, means operable after the application of the adhesive to move the plate to force the

second end wall inwardly upon the first end wall, while the holding members remain in position, and form the side walls of the top into flaps, means for applying adhesive to the inner faces of the flaps, and means for folding the flaps inwardly upon the infolded end walls.

3. In a machine for closing and sealing the tops of bundles, the combination of means for advancing a bundle with an open top in upright position, a pair of folding members movable in a horizontal plane for forcing one end wall of the top inwardly, a pair of holding members movable on a horizontal axis to engage the inner surface of the second end wall of the top, a plate engageable with the outer surface of the second end wall between the holding members, means for applying adhesive to the inner surface of the second end wall, means operable after the application of the adhesive to move the plate to force the second end wall inwardly upon the first end wall, while the holding members remain in position, and form the side walls of the top into flaps, means for applying adhesive to the inner faces of the flaps, and means for folding the flaps inwardly upon the infolded end walls.

4. In a machine for closing and sealing the tops of bundles, the combination of means for advancing a bundle with an open top in upright position, a pair of folding members mounted to swing on vertical axes on opposite sides of the path of travel of the bundle and movable to force one end wall of the top inwardly, a pair of holding members movable into the top to engage the inner surface of the second end wall of the top, a plate engageable with the outer surface of the second end wall between the holding members, means for applying adhesive to the inner surface of the second end wall, means operable after the application of the adhesive to move the plate to force the second end wall inwardly upon the first end wall, while the holding members remain in position, and form the side walls of the top into flaps, means for applying adhesive to the inner faces of the flaps, and means for folding the flaps inwardly upon the infolded end walls.

5. In a machine for closing and sealing the tops of bundles, the combination of means for advancing a bundle with an open top in upright position, a pair of folding members movable in a horizontal plane for forcing one end wall of the top inwardly, a pair of holding members mounted on a horizontal axis above the path of travel of the bundle and movable into the top to engage the inner surface of the second end wall of the top, a plate engageable with the outer surface of the second end wall between the holding members, means for applying adhesive to the inner surface of the second end wall, means operable after the application of the adhesive to move the plate to force the second end wall inwardly upon the first end wall, while the holding members remain in position, and form the side walls of the top into flaps, means for applying adhesive to the inner faces of the flaps, and means for folding the flaps inwardly upon the infolded end walls.

6. In a machine for closing and sealing the tops of bundles, the combination of means for advancing a bundle with an open top in upright position, a pair of folding members movable in a horizontal plane for forcing one end wall of the top inwardly, a pair of holding members movable in parallel vertical planes to engage the inner

surface of the second end wall of the top, a plate engageable with the outer surface of the second end wall of the top between the holding members, means for applying adhesive to the inner surface of the second end wall, means operable after application of the adhesive to move the plate to force the second end wall inwardly upon the first end wall while the holding members remain in position and form the side walls of the top into flaps, means for applying adhesive to the inner faces of the flaps, and means for folding the flaps inwardly upon the infolded end walls.

7. In a machine for closing and sealing the tops of bundles, the combination of means for advancing a bundle with an open top in upright position, a pair of folding members movable in a horizontal plane for forcing one end wall of the top inwardly, a pair of holding members movable into the top to engage the inner surface of the second end wall of the top, a plate engageable with the outer surface of the second end wall between the holding members, means for applying adhesive to the inner surface of the second end wall, means operable after the application of the adhesive to move the plate to force the second end wall inwardly upon the first end wall, while the holding members remain in position and cooperate with the plate to form the side walls of the top into flaps standing vertically, means for folding the flaps outwardly, means for applying adhesive to the upper surfaces of the flaps, and means for folding the flaps inwardly upon the infolded end walls.

8. In a machine for closing and sealing the tops of bundles, the combination of conveying means for advancing a bundle with an open top in upright position to and beyond a station with the bundle pausing at the station, a pair of folding members movable in a horizontal plane to force inwardly one end wall of the top of a bundle at rest at the station, a pair of holding members mounted adjacent the station and movable to engage the inner surface of the second end wall of the top, a plate disposed at the station and engageable with the outer surface of the second end wall of the top between the holding members, means for applying adhesive to the inner surface of the second end wall, means operable after application of the adhesive to move the plate to force the second end wall inwardly upon the first end wall and around the edges of the holding members to form the side walls of the top into flaps, means beyond the station for applying adhesive to the inner faces of the flaps as the bundle moves away from the station, and means beyond the adhesive-applying means for folding the flaps inwardly upon the infolded end walls as the bundle moves along.

9. In a machine for closing and sealing the tops of bundles, the combination of conveying means for advancing a bundle with an open top in upright position to and beyond a station with the bundle pausing at the station, a pair of folding members movable in a horizontal plane to force inwardly one end wall of the top of a bundle at rest at the station, a pair of holding members mounted adjacent the station and movable to engage the inner surface of the second end wall of the top, a plate disposed at the station and engageable with the outer surface of the second end wall of the top between the holding members, means for applying adhesive to the inner surface of the second end wall, means operable after application of the adhesive to move

the plate to force the second end wall inwardly upon the first end wall and around the edges of the holding members to form the side walls of the top into flaps, means beyond the station for folding the flaps outwardly, means for applying adhesive to the upper faces of the flaps, and means for folding the flaps inwardly upon the infolded end walls, the last three means operating upon the bundle as it is moving away from the station.

10. In a machine for closing and sealing the tops of bundles, the combination of a pair of members operable to fold inwardly one end wall of the top of the bundle, a pair of holding members operable to engage the inner surface of the second end wall of the top, a plate engageable with the outer surface of the second end wall between the holding members, and means for operating the plate to fold the second end wall of the top inwardly upon the previously infolded end wall and around the edges of the holding members to form the side walls of the top into flaps.

11. In a machine for closing and sealing the tops of bundles, the combination of a pair of members movable in a horizontal plane and operable to fold inwardly one end wall of the top of the bundle, a pair of holding members operable to engage the inner surface of the second end wall of the top, a plate engageable with the outer surface of the second end wall between the holding members, and means for operating the plate to fold the second end wall of the top inwardly upon the previously infolded end wall and around the edges of the holding members to form the side walls of the top into flaps.

12. In a machine for closing and sealing the tops of bundles, the combination of a pair of members swinging about vertical axes and operable to fold inwardly one end wall of the top of the bundle, a pair of holding members operable to engage the inner surface of the second end wall of the top, a plate engageable with the outer surface of the second end wall between the holding members, and means for operating the plate to fold the second end wall of the top inwardly upon the previously infolded end wall and around the edges of the holding members to form the side walls of the top into flaps.

13. In a machine for closing and sealing the tops of bundles, the combination of a pair of members operable to fold inwardly one end wall of the top of the bundle, a pair of holding members movable in parallel vertical planes and operable to engage the inner surface of the second end wall of the top, a plate engageable with the outer surface of the second end wall between the holding members, and means for operating the plate to fold the second end wall of the top inwardly upon the previously infolded end wall and around the edges of the holding members to form the side walls of the top into flaps.

14. In a machine for closing and sealing the tops of bundles, the combination of a pair of members operable to fold inwardly one end wall of the top of the bundle, a pair of holding members mounted to swing on a horizontal axis and operable to engage the inner surface of the second end wall of the top, a plate engageable with the outer surface of the second end wall between the holding members, and means for operating the plate to fold the second end wall of the top inwardly upon the previously infolded end wall and around the edges of the holding members to form the side walls of the top into flaps.

15. In a machine for closing and sealing the tops of bundles, the combination of a pair of folding plates mounted on respective vertical shafts, means for rocking the shafts to cause the plates to engage and fold inwardly one end wall of the top of a bundle, a horizontal shaft, a pair of parallel holding plates on the horizontal shaft, means for rocking the horizontal shaft to cause the holding plates to engage the inner surface of the second end wall of the bundle, a second horizontal shaft, a plate mounted thereon to be parallel to the axis of the shaft and between the planes of movement of the holding plates, and means for rocking the second horizontal shaft to cause the plate thereon to fold the second end wall inwardly over the previously infolded end wall and around the edges of the holding plates to form the side walls of the top into flaps.

16. In a machine for closing and sealing the tops of bundles, the combination of a pair of members operable to fold inwardly one end wall of the top of the bundle, a pair of holding members operable to engage the inner surface of the second end wall of the top, a plate engageable with the outer surface of the second end wall between the holding members, means for applying adhesive to the inner surface of the second end wall, and means for operating the plate to fold the second end wall of the top inwardly upon the previously infolded end wall and around the edges of the holding members to form the side walls of the top into flaps.

17. In a machine for closing and sealing the tops of bundles, the combination of a pair of folding plates mounted on respective vertical shafts, means for rocking the shafts to cause the plates to engage and fold inwardly one end wall of the top of a bundle, a horizontal shaft, a pair of parallel holding plates on the horizontal

shaft, means for rocking the horizontal shaft to cause the holding plates to engage the inner surface of the second end wall of the bundle, a second horizontal shaft, a plate mounted thereon to be parallel to the axis of the shaft and between the planes of movement of the holding plates, means for applying adhesive to the inner surface of the second end wall of the top, and means for rocking the second horizontal shaft to cause the plate thereon to fold the second end wall inwardly over the previously infolded end wall and around the edges of the holding plates to form the side walls of the top into flaps.

18. In a machine for closing and sealing the tops of bundles, the combination of a pair of members operable to fold inwardly one end wall of the top of the bundle, a pair of holding members operable to engage the inner surface of the second end wall of the top, a plate engageable with the outer surface of the second end wall between the holding members, means for applying adhesive to the inner surface of the second end wall, means for operating the plate to fold the second wall of the top inwardly upon the previously infolded end wall and around the edges of the holding members to form the side walls of the top into flaps, means for advancing the bundle beyond the plate, plows acting on the flaps, as the bundle moves, to turn the flaps outwardly, means for applying adhesive to the upper faces of the flaps, and a pair of plates each reciprocating at an angle to the path of travel of the bundle and operable to fold the flaps down upon the infolded end walls, as the bundle moves along its path.

WILLIAM L. IRVINE.
